HYDRAULIC WINDING MACHINE

Filed Jan. 6, 1950

Fig. 1.

UNITED STATES PATENT OFFICE

2,558,564

HYDRAULIC WINDING MACHINE

Harold A. Jensen, Syracuse, N. Y., assignor to
General Electric Company, a corporation of
New York

Application January 6, 1950, Serial No. 137,179

2 Claims. (Cl. 242—9)

1

This invention relates to winding machines and, in particular, to an improved arrangement for transferring wire from a spool to a resistor, coil or the like, wherein it is important that the wire be arranged at a predetermined pitch and at a predetermined tension during such transfer.

While winding machines are not new in the art, since machines are in use that axially move a piece of work while wire is being wound thereon to locate the wire at a predetermined pitch, yet because of the inherent difficulties encountered in mechanical arrangements of this type, there is still the need in the art for an improved winding machine.

Heretofore, with mechanically operated winding machines, it has been necessary to change combinations of cams and ratchets or the like in order to vary a pitch setting. This usually involved troublesome time-consuming operations which decreased the efficiency of operator and machine.

It is an object of this invention to provide an improved coil winding machine.

It is a further object of this invention to provide a hydraulic winding machine in which predetermined settings may be varied without interchanging parts of the machine.

It is a still further object of this invention to provide a winding machine that has a greater efficiency, that requires less horsepower to operate, and that will operate at higher winding speeds.

Broadly, this invention comprises an apparatus that hydraulically moves a core in an axial direction within a chuck while the chuck and core are rotating, and wire is being wound under pre-selected tension on the core. The chuck leads the wire onto the core and the axial movement thereof gives a predetermined pitch to the wire being wound on the core.

Further objects and advantages of this invention will become apparent and the invention will be more clearly understood from the following description referring to the accompanying drawing, and the features of novelty which characterize this invention will be pointed out with particularity in the claims annexed to and forming a part of this specification.

Referring to the drawings, Fig. 1 is a view of a section taken through the longitudinal axis of this improved device; Fig. 2 is an end view of the chuck arrangement used to hold a flat core that is being wound; and Fig. 3 is a similar end view of a modified chuck arrangement for winding round cores.

In Fig. 1, a cylindrical housing 1 is shown revolvably supported in a pair of bearings 2 and 3 which, in turn, are secured to a base plate (not shown). A pulley 4 is secured to housing 1 and rotates it in bearings 2 and 3 when pulley 4 is rotated by a motor driven belt or the like (not shown).

Internally, cylinder 1 is divided by a partition 5 into an upper storage portion 6 and a lower storage portion 7. A passageway 8 is provided in partition 5 to permit the passage of a liquid from upper storage portion 6 to a lower storage portion 7. A needle valve 9 controls the flow of the liquid through passageway 8. A quantity of hydraulic fluid 10 is contained within lower storage portion 7 and is held under pressure by an expandable diaphragm 11. A plug 12 is secured into the lower end of cylindrical housing 1 to seal lower storage portion 7 from bearing 3. A protrusion 13, which is an integral part of plug 12, extends through bearing 3 and is rotatable therein.

A fluid pump 14 is secured as by bushing 21 to protrusion 13 to be rotatable therewith. Pump 14 comprises a cylinder 15 and a piston 16. Piston 16, in turn, is secured as by a crank pin 16a to a crank arm 17. Crank arm 17 is rotatable about a shaft 18 whose axis is out of alignment with the axis of cylindrical housing 1. A bearing 19 is provided on shaft 18 to facilitate the rotation of crank arm 17 about the shaft. With this structure rotary motion is imparted to crank arm 17 by piston 16 through its pin 16a.

Since shaft 18 is out of alignment with the axis of cylindrical housing 1, then, at a position 180 degrees from that shown in Fig. 1, piston 16 is deeper into cylinder 15 than it is in the position shown. Consequently, as housing 1, plug 12, protrusion 13, pump 14, piston 16, and crank arm 17 rotate at the same number of revolutions per minute, a reciprocating pump stroke is imparted to piston 16.

The alignment of shaft 18 with the axis of cylindrical housing 1 is varied by an arrangement which comprises a pitch setting dial 20 and a threaded adjusting screw 21 supported in a fixed block 22. By varying the setting of dial 20, screw 21 moves axially in relation to block 22 and thereby moves a bushing 23 that varies the position of shaft 18. With this arrangement, the displacement of shaft 18 relative to the axis of housing 1 and, hence the length of stroke of piston 16, can be varied.

Within plug 12, protrusion 13 and pump 14, a valving arrangement is provided for the pump. Specifically, a port chamber 24 is provided in plug

12. A longitudinal passageway 25 connects port chamber 24 with a pump chamber 26 which, in turn, is connected to cylinder 15. A bushing 27 is positioned in longitudinal passageway 25 and extends across the joint of protrusion 13 and pump 14 to seal it.

A duct 28 of smaller diameter than port chamber 24 extends from one end of the chamber to a tube 29 which connects duct 28 to an upper section of lower storage portion 7. A second duct 30 of larger diameter than port chamber 24 extends from the other end of the chamber. A tube 31 connects duct 30 to upper storage portion 6. A ball 32 having a diameter larger than duct 28 is positioned between port chamber 24 and duct 28, while a second ball 33 axially slidably in duct 30 is positioned between port chamber 24 and duct 30. A spring 34 is positioned between the two balls, while a second spring 35 maintains ball 33 in contact with the end of duct 30 that connects with port chamber 24. The tension on spring 35 is adjustable by set screw 36.

With this valving arrangement, at the suction stroke of pump 14 the pressure in port chamber 24 is less than that in tube 29 or tube 31. Ball 33, because of the pressure on spring 35, seals tube 31 from port chamber 24, but the pressure of fluid in tube 29 forces ball 32 towards ball 33, allowing fluid to enter from lower storage portion 7 into port chamber 24. On the pressure stroke of pump 14, the pressure of the liquid in port chamber 24 is greater than that in either tube 29 or 31. The pressure of the liquid plus the pressure of spring 34 on ball 32 seals the port chamber from tube 29, but the pressure of spring 34 plus the pressure of the liquid forces ball 33 away from ball 32 to allow liquid to pass from port chamber 24 into tube 31.

This cycle is continuously repeated while pulley 4 is being driven to rotate cylindrical housing 1 and pump 14. Consequently, there is an intermittent pulsation that forces a quantity of liquid, determined by the length of pump stroke, into tube 31.

A plunger 37 is provided in upper storage portion 6. The plunger has a diameter substantially equal to the inner diameter of the upper storage portion and is in slidable engagement therewith. Actually, plunger 37 and upper storage portion 6 form a piston and cylinder arrangement. A plunger rod 38 extends upwardly from plunger 37 through a cap 39 which closes the upper end of upper storage portion 6. Cap 39, in addition to closing the upper end of storage portion 6, has an extended portion 40 that rides within bearing 2 and guides the rotation of cylindrical housing 1. A spring 41 is positioned between cap 39 and plunger 37 and biases the plunger away from the cap.

The slugs of liquid which are cyclically forced by pump 14 through tube 31 enter the upper storage portion through a vent 42 and force plunger 37 towards cap 39 in opposition to the bias of spring 41. Since pump 14 goes through a complete cycle every revolution of cylindrical housing 1, plunger 37 is raised a predetermined distance for every complete revolution of cylindrical housing 1 and, consequently, a point on plunger rod 38 is given a lead depending upon the amount that plunger 37 is raised each revolution.

A chuck 43 is secured above bearing 2 to the upper end of cap 39 and is rotatable therewith. The chuck comprises a bushing 44 and a pair of chuck jaws 45. A flat coil form 46, which may be of mica or other suitable material, is held

by jaws 45 and rotates with the cylindrical housing 1.

The upper end of plunger rod 38 is provided with a threaded bore 47 for accommodating an adjusting screw 48. Rod 38 and adjusting screw 48 rotate with housing 1 and, in addition, an axial movement is imparted to the rod and adjusting screw by the liquid that is pumped through vent 42 into upper storage portion 6. Consequently, the flat coil form 46, which is in slidable engagement with chuck jaws 45, while rotating at the same number of revolutions as housing 1, is pushed upwardly by adjusting screw 48 at a rate that is predetermined by the length of pump stroke of piston 15 in cylinder 16.

If it is intended to wind strip 46 with a resistance wire, the resistance wire 49 is secured to the top of the strip and cylindrical housing 1 is rotated, whereupon resistance wire 49 is wound upon strip 46 at a predetermined pitch.

If any of the usual tensioning apparatus is used, such as that indicated at 49a, then resistance wire 49 is applied to strip 46 under a tension, as required. The upper end of chuck jaws 45 serve as a guide to lead resistance wire 49 onto strip 46.

The details of chuck 43 are more clearly illustrated in Fig. 2. Specifically, each of the jaws 45 comprises a bar of springy metal or the like that is secured to bushing 44 by some means, such as by welding. The jaws are mounted in alignment 180 degrees apart. Each of the jaws has a V-shaped groove 50 for gripping strip 46. With this structure, strip 46 is securely, but slidably held by the friction between chuck jaws 45 and the edges of the strip.

Obviously, chuck jaws 45 could be arranged to accommodate any shape core, for instance, they could be made semi-circular, as jaws 51 shown in Fig. 3, whereupon a circular core 52, that is provided with any sort of a protrusion 53, could be rotated with housing 1 while a lead is being imparted to it by plunger rod 38 and adjusting screw 48.

In the operation of this improved winding machine, a coil form adapted to fit the chuck jaws in use is slid axially into the chuck and a wire of the type to be wound is secured to the core. Needle valve 9 is closed and pulley 4 is driven by some means, such as a motor (not shown). Diaphragm 14, acting on hydraulic fluid 16 in lower storage portion 7, forces the fluid through tube 29 into pump 14, which, in turn, forces a slug of fluid into tube 31 during each revolution of pulley 4. The size of the slug of liquid is predetermined by the position of pitch setting dial 20, which regulates the amount of eccentricity of crank arm 17. The slug of liquid passes from tube 31 through vent 42 into upper storage portion 6. The liquid in the upper storage portion forces plunger 37, plunger rod 38, and adjusting screw 48 axially through cap 39. The combination of the rotation of housing 1 and chuck 43 with the axial motion of adjusting screw 48 winds wire 49 about core 46 at a predetermined pitch.

It is obvious that a protrusion may be provided on cylindrical housing 1 that will trip a revolution counter (not shown) to shut off the driving motor after a predetermined number of revolutions. In such case, an operator merely inserts a core into chuck 43, starts the motor, allows it to run its predetermined number of revolutions, and then secures the end of the wire to the core, whereupon a completely wound core is formed.

After each core is wound, it is necessary to release needle valve 9, whereupon spring 41, which is biased between cap 39 and plunger 37, forces plunger 37 away from cap 39, and the hydraulic fluid is forced from upper storage portion 6 through passageway 8 into lower storage portion 7. When needle valve 9 is again closed, the apparatus is ready to wind another core.

Modifications of this invention will occur to those skilled in the art and it is desired to be understood, therefore, that this invention is not to be limited to the particular embodiment disclosed, but that the appended claims are meant to cover all the modifications which are within the spirit and scope of this invention.

What I claim as new and desire to secure by Letters Patent of the United States is:

1. In a machine adapted to wind wire on a core at a predetermined pitch, a rotatable cylinder having an upper and a lower hydraulic fluid storage compartment, a partition between said compartments, said partition defining a fluid passageway joining said compartments and including a valve for closing said passageway, means for rotating said cylinder, a pump comprising a cylinder and piston arrangement rotatable with said cylinder, means connecting the input of said pump to said lower fluid storage compartment, means connecting the output of said pump to said upper storage compartment, a quantity of hydraulic fluid adapted to be held in said lower storage compartment, expandable means within said lower compartment for exerting a pressure on said hydraulic fluid in said lower storage compartment, eccentric means for imparting a cycling transverse movement to said piston while it is being rotated, means for varying the eccentricity of said eccentric means, a plunger in sliding engagement with said upper storage compartment, said plunger being biased to force fluid through said partition passageway, said pump forcing a predetermined quantity of fluid into said upper storage compartment to lift said plunger when said partition passageway valve is

- closed, a core adapted to have wire wound thereon, a chuck including jaws adapted to lead wire onto said core and to position said core while allowing axial slide movement thereof, means interposed between said plunger and said core to axially slide said core a predetermined distance with each revolution of said cylinder, and means including said chuck for leading a wire onto said core under tension, whereby said wire is wound on said core at a predetermined pitch.
2. In a machine adapted to wind wire on a core at a variable pitch that is constant for any one setting, a core adapted to have a wire wound thereon, a chuck including jaws adapted to lead wire onto said core and to hold said core while allowing axial movement thereof, means for supporting said chuck including a rotatable cylinder, said cylinder comprising an upper and a lower fluid storage compartment, means including a pump rotatable with said cylinder for forcing fluid from said lower to said upper storage compartment, means for varying the fluid output per cycle of said pump, a plunger axially movable in said upper fluid storage compartment, said plunger being adapted to move axially in response to the quantity of liquid forced by said pump into said upper storage compartment, means interposed between said plunger and said core for axially sliding said core a predetermined distance for each revolution of said cylinder, and means including said chuck for leading a wire onto said core under tension, whereby said wire is wound on said core at a predetermined pitch.
